UNITED STATES PATENT OFFICE.

CHARLES D. YOUNG, OF ALTOONA, PENNSYLVANIA.

LOCOMOTIVE SUPERHEATER APPARATUS.

1,089,807.

Specification of Letters Patent. Patented Mar. 10, 1914.

Application filed October 1, 1913. Serial No. 792,702.

To all whom it may concern:

Be it known that I, CHARLES D. YOUNG, a citizen of the United States, residing at Altoona, in the county of Blair and State of Pennsylvania, have invented certain new and useful Improvements in Locomotive Superheater Apparatus, of which the following is a specification.

The invention relates to an apparatus whereby superheated steam can be utilized with the air pump of a locomotive, thus increasing the economy of operation of such pumps. The objection heretofore in utilizing superheated steam for this purpose was due to the fact that when the pump was not in operation and no steam was flowing through the highly heated superheater pipes, such pipes would overheat and burn out, particularly when the locomotive was running, as a result of the absence of the flowing steam which would otherwise absorb the heat and prevent the pipes attaining an unduly high temperature. My invention has for its primary object, the overcoming of this difficulty, and to this end a supplemental pump-supplying superheater is provided and a mechanism is employed whereby the steam superheated in the supplemental superheater and not required for operating the pump may be automatically directed to the main body of steam passing to the locomotive cylinders when the locomotive is running, so that a stoppage of the pump during the time the locomotive is running and the supplemental superheater pipes are being highly heated does not cause a stoppage of the flow of steam through such pipes.

The specific means for accomplishing this function include a valve in a bypass leading from the steam pump supply pipe to the main portion of the superheater and arranged to open automatically when steam is admitted past the throttle valve to the dry pipe of the locomotive. One embodiment of the invention is illustrated in the accompanying drawings, wherein—

Fig. 1 is a side elevation of the front end of the locomotive with my improved apparatus applied thereto, a portion of the wall or casing of the locomotive being broken away, Fig. 2 is a transverse section through the smoke box of the locomotive, and shows the superheater and co-operating air pump mechanism in front elevation, Fig. 3 is an enlarged vertical section through the control-

ling valve employed, and Fig. 4 is a horizontal section on the line IV—IV of Fig. 2.

The superheater headers are made in an integral casting extending across the smoke box above the fire tubes as indicated in Figs. 1 and 2, and the casting is divided into four chambers 1, 2, 3, and 4 (Fig. 4), by the vertical walls 5 and 6. The chambers 1 and 2 constitute the main superheater headers for supplying steam to the cylinders of the locomotive, while the chambers 3 and 4 constitute the headers for the supplemental superheater for supplying steam to the steam cylinders of the air pump.

The chamber 1 receives steam from the boiler through the dry pipe 7 leading to the steam dome 8 and having its inlet end controlled by the throttle in the usual way. Superheater tubes 9 lie in the fire tubes 10, and each have one end connected to the chamber 1, and the other end connected to the chamber 2, the tubes taking into the bottoms of the chambers, and the arrangement being one which is well known in the art. Only a part of the tubes 9 are illustrated in Fig. 2, but it will be understood that one or more of such tubes lie in each of the fire tubes. At each end of the chamber 2 is an outlet pipe 11, one of such pipes leading to one of the cylinders of the engine and the other leading to the other cylinder, via the steam chests in the ordinary way. It will be seen that steam supplied to the chamber 1 through the dry pipe 7 passes through the pipes 9 where it is superheated, and then passes to the chamber 2 from which it is delivered through the outlet pipe 11. The headers 1 and 2 and the tubes 9 as above described constitute what may be termed the main superheater to distinguish from the supplemental superheater which will now be described.

The supplemental superheater comprises the chambers or headers 3 and 4 and the tubes 12, such tubes lying in the fire tubes as illustrated, and each having one of their ends connected to the chamber 3 and the other end connected to the chamber 4. Steam is admitted to the chamber 4 by the pipe 13 (Figs. 1, 2, and 4). By reference to Fig. 1 it will be seen that this pipe 13 opens into the steam dome 8, so that steam is constantly supplied to the header chamber 3 independently of the supply of steam to the main superheater from the dry pipe 7. The steam

supplied to the header 4 by the pipe 13 passes through the superheater pipes 12 and into the chamber 3. Steam is delivered from the chamber 3 to the steam cylinders 14 of the air pump 15, by means of the pipe 16. In this pipe 16 are located manually operable valve 17', and a governor 18, which may be of any approved type, but is preferably the ordinary Westinghouse governor.

In order to prevent the supplemental superheater tubes 12 from overheating while the locomotive is running, and when the supply of steam to the steam cylinders 14 is cut off by the pump governor 18, and in order to utilize the supplemental superheater for use in conjunction with the main superheater, the apparatus involving the pipes 17, 18, and 19, and the mechanism in the casing 20 is employed. The pipe 17 leads from the pipe 16 to the valve casing 20 (Fig. 1), while the pipe 18 leads from the casing 20 to the header chamber 2 of the main superheater (Figs. 2 and 4). The pipe 19 leads from the dry pipe 7 to the lower end of the casing 20. In the casing 20 are the differential pistons 21 and 22 carried by the stem 23, and the slide valve 24 also carried by the stem 23. A small passage 24' provides for the release of pressure which accumulates upon the upper side of the piston 21.

When the parts are in the position indicated in Fig. 3 steam is admitted to the space between the pistons 21 and 22, from the pipe 17, and the slide valve 24 closes the port leading to the pipe 18. The parts will occupy the position indicated, and be positively held in such position when pressure is applied through the pipe 17, by reason of the fact that the piston 22 is larger than the piston 21, but when pressure is applied through the pipe 19 from the dry pipe 7 the pistons 21 and 22 and the valve 24 will be moved up, uncovering the end of the pipe 18 and permitting a discharge of steam therethrough to the chamber 2 of the main superheater.

It will be seen that when the engine is standing and no steam is being supplied through the dry pipe 7, the throttle being closed, the valve 24 will occupy the position indicated in Fig. 3, and no steam will be permitted to escape through the pipe 18 to the chamber 2. At such time any steam supplied through the pipe 13 and supplementary superheater will pass to the steam cylinders 14 operating the air pump, and the passage between the pipes 17 and 18 must necessarily be closed, as otherwise there would be a discharge of steam to the steam cylinders of the locomotive, via the pipe 18 and chamber 2, which would tend to cause the locomotive to move ahead. On the other hand when the engine is running and steam is being supplied through the dry

pipe 7, it is necessary that the valve 24 should be in its upper position, thus permitting a discharge of steam through the pipe 18, as otherwise the supplemental superheater would be of no use when the operation of the steam cylinders 14 had stopped, and as a result of the non-circulation of steam through the superheater pipes of the supplemental superheater, such pipes would tend to become overheated, and burn out. As soon therefore as the engine is started the valve 24 is opened, and any steam which is not required for operation of the cylinders 14 is discharged through the pipe 18 to the main superheater chamber 2 and utilized in the operation of the locomotive pistons. The pressure in the chamber 2, and the size of the pipe 16 are such that there is always sufficient pressure in the pipe 16 to operate the cylinders 14 of the air pump, even when the passage between the pipes 17 and 18 is open.

It will be understood that the invention is not limited to the particular kind of superheaters illustrated, the only requirement being that there be a main and a supplemental superheater, and that automatic means be provided for connecting the supplemental superheater to the main superheater when the throttle of the engine is open. This automatic actuation is preferably accomplished by means of a supply of steam from the dry pipe in the manner illustrated, but the invention contemplates the use of any means whatsoever whereby the communication between the two superheaters is opened automatically when the throttle is opened. It will also be understood that the form of communication between the two superheaters may be varied, and that the pipe 18 does not necessarily lead into the header chamber 2, the only requirement being that this supply of steam from the supplemental heater be added to the main body of steam for supplying the locomotive cylinders, and the term "communication" referring to the connection between the two superheaters is used in its broad sense, and covers any arrangement whereby the two supplies of steam are merged, regardless of the point of merger.

What I claim is:

1. In combination in locomotive superheater apparatus for supplying a portion of the superheated steam to the steam cylinder of an air pump, a main superheater for supplying steam to the locomotive cylinders, a supplemental superheater, a connection for supplying steam to said supplemental superheater from the boiler, a connection from the supplemental superheater to the said air pump steam cylinder, and automatic means whereby the supplemental superheater is placed in communication with the main superheater when steam is supplied to

the said main superheater from the boiler, and whereby such communication is cut off when the supply of steam to the main superheater is cut off.

plemental superheater to the steam cylinder of the air pump, a communication from the boiler for supplying steam to the main superheater, a separate communication for supplying steam from the boiler to the supplemental superheater, and automatic means governed by the supplying and cutting off of steam to the main superheater, for opening and closing the communication for supplying steam from the supplemental superheater to the locomotive cylinder. 60 65

- 5 2. In combination in locomotive superheater apparatus for supplying a portion of the superheated steam to the steam cylinder of an air pump, a main superheater for supplying steam to the locomotive cylinders, a
- 10 supplemental superheater, a connection from the supplemental superheater to the said air pump steam cylinder, a communication from the supplemental to the main superheater, and controlling means therein operated by supplying and cutting off the supply of steam to the main superheater for opening and closing the said communication.
- 15

6. In combination in locomotive superheater apparatus for supplying a portion of the superheated steam to the steam cylinder of an air pump, a main superheater for supplying steam to the locomotive cylinders, a supplemental superheater provided with a communication for supplying steam to a main locomotive cylinder, a communication for supplying steam from the supplemental superheater to the steam cylinder of the air pump, a communication from the boiler for supplying steam to the main superheater, a separate communication for supplying steam from the boiler to the supplemental superheater, a valve in the communication leading from the supplemental superheater to the engine cylinder normally held closed by steam pressure from the said separate communication, and a pipe leading to the valve from the communication for supplying steam to the main superheater and adapted to supply steam to open the said valve when steam is supplied to the last mentioned communication. 70 75 80 85 90

3. In combination in locomotive superheater apparatus for supplying a portion of the superheated steam to the steam cylinder of an air pump, a main superheater in communication with the dry pipe of the locomotive for supplying steam to the locomotive cylinders, a supplemental superheater, a separate connection for supplying steam from the boiler to the supplemental superheater, a communication between the two superheaters, a valve in the said communication, and means operated by pressure from the dry pipe for opening the said valve.

7. In combination in locomotive superheater apparatus for supplying a portion of the superheated steam to the steam cylinder of an air pump, two superheaters having independent connections to the boiler, 95 one of which is controlled by the throttle, and such latter arranged to supply the locomotive cylinders and the other the steam cylinder of the air pump, and means for automatically connecting the supplies of 100 steam from the two superheaters when the throttle is opened.

4. In combination in locomotive superheater apparatus for supplying a portion of the superheated steam to the steam cylinder of an air pump, a main superheater in communication with the dry pipe of a locomotive for supplying steam to the locomotive cylinders, a supplemental superheater, a separate connection for supplying steam from the boiler to the supplemental superheater, a communication between the two superheaters, and automatic means for opening the said communication when steam is supplied through the dry pipe and for closing it when the supply of steam is cut off from the said dry pipe.

throttle is opened.
In testimony whereof I have hereunto signed my name in the presence of the two subscribed witnesses.

5. In combination in locomotive superheater apparatus for supplying a portion of the superheated steam to the steam cylinder of an air pump, a main superheater for supplying steam to the locomotive cylinders, a supplemental superheater provided with a communication for supplying steam to a main locomotive cylinder, a communication for supplying steam from the sup-
